(57) **CLAIM**

The ornamental design for a monitor, as shown and described.

DESCRIPTION

FIG. 1 is a perspective view of a monitor, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another right-side view a monitor of FIG. 1, showing a display part of the monitor in a slant position;

FIG. 9 is a perspective view of a monitor of FIG. 1, in which the unclaimed display part of the monitor in broken line, is removed to further show the remaining portion of the claimed design;

FIG. 10 is a front view of the remaining portion of FIG. 9;

FIG. 11 is a rear view of the remaining portion of FIG. 9;

FIG. 12 is a left-side view of the remaining portion of FIG. 9;

FIG. 13 is a right-side view of the remaining portion of FIG. 9;

FIG. 14 is a top plan view of the remaining portion of FIG. 9;

FIG. 15 is a bottom plan view of the remaining portion of FIG. 9; and,

FIG. 16 is a rear perspective view of a monitor of FIG. 1.

The broken lines are for illustrative purposes only and form no part of the claimed design. The shade lines in the figures show contour and not surface ornamentation. The dot-dash lines in FIGS. 3 through 9 and 11 through 16 define unclaimed boundaries of the claimed design and form no part of claimed design.
